His. Attorney

UNITED STATES PATENT OFFICE.

WILLIAM H. RIPLEY, OF HARTFORD, CONNECTICUT, ASSIGNOR TO THE WHITLOCK COIL PIPE COMPANY, OF WEST HARTFORD, CONNECTICUT, A CORPORATION OF CONNECTICUT.

HEAT-EXCHANGE APPARATUS.

Application filed March 10, 1922. Serial No. 542,566.

To all whom it may concern:

Be it known that I, WILLIAM H. RIPLEY, a citizen of the United States, and resident of Hartford, county of Hartford, State of Connecticut, have invented certain new and useful Improvements in a Heat-Exchange Apparatus, of which the following is a specification.

This invention relates, generally, to apparatus wherein an exchange of heat is effected from one fluid to another by passing one of the fluids through a plurality of pipes, and the other fluid about the pipes. The device may be used either as a cooler or heater, as desired, and has a wide application in that fluids of any sort, and whether in the liquid, gaseous or vaporous state, can be heated or cooled. The device finds peculiar application as an oil heater or cooler, but, as stated, it may be employed for other uses.

The object of the present invention is to provide a heat exchange apparatus of the type described having various features of novelty and advantage. More particularly, the aim of the invention is to provide an apparatus of this sort wherein one medium, for instance the fluid to be cooled, is passed through one group of tubes within a shell in one direction, and then through another group of tubes in the opposite direction; and the other medium, for instance the cooling fluid, is caused to flow in a serpentine or broken path without stratification through the shell about the tubes and in a general direction opposite or counter to the flow of the fluid within the tubes. The apparatus is of very simple construction, and, therefore, may be cheaply manufactured and installed, and it is particularly effective in operation in that the fluid within the shell, while flowing generally counter to the fluid in all of the pipes, has a relatively long path so arranged that the fluid is passed back and forth transversely of the pipes and is so baffled that the greatest efficiency is obtained. A further aim of the invention is to provide an improved construction wherein all possibility of one of the mediums or fluids leaking to the space occupied by the other fluid and thus contaminating one another is prevented.

In the accompanying drawing, wherein I

have shown for illustrative purposes one embodiment which the invention may take, 55

Fig. 1 is a view taken centrally and longitudinally through my improved heat ex- change apparatus; and

Fig. 2 is a transverse sectional view.

Referring to the drawing in detail, *a* de- 60 notes a shell or casing, which may be of usual construction; *b* denotes the tubes of one group and *b'* the tubes of the other group. The forward ends of the tubes *b* and *b'* are expanded into a tube sheet *c* 65 forming a part of the service header *d* which is transversely divided by a partition *e* into two chambers, one of the chambers being provided with an inlet *f* and the other an outlet *g*. The other ends of the tubes may 70 be connected together by U-bends *h*, as shown in the drawing. The casing *a*, at its forward end, is provided with an inlet *k* and a diametrically disposed outlet *l*.

It will be noted that the tube sheet *c* 75 forms one wall of the service header but does not close or form the end wall of the casing *a*. The end wall of the casing *a* is constituted by a second tube sheet 10 bolted to the end of the casing and having open- 80 ings through which the tubes pass and in which the tubes are expanded. It will be noted that, with this arrangement, the forward end of the tubes are expanded in a pair of tube sheets, one tube sheet closing 85 the forward end of the casing and the other forming a wall of the service header, and that with this construction, there is no danger of the medium within the shell and about the tubes leaking into the service 90 header, or vice versa, and thus all possibility of contaminating one of the mediums by the mixture therewith of the other medium is eliminated. Furthermore, any leakage between the pipes and the tube sheets *c* or 95 10 may be readily seen, and thus the leak can be repaired before any material amount of damage is done. Apparatus of this type are sometimes employed as a combined oil 100 heater and cooler, a crude oil to be heated being passed about the pipes and a refined oil, which has already been heated and the heat of which is to be utilized to raise the temperature of the crude oil, is passed through the tubes, and, heretofore, not in- 105 frequently, the crude oil has leaked through

a joint and become mixed with the refined oil, resulting, in some instances, in the contamination of a large amount of the refined oil before the leak was discovered. With 5 the present arrangement, this cannot occur.

Positioned between the two groups of tubes b and b' and longitudinally dividing the casing, except at its rear end, is a division plate 15, preferably in the form of a 10 sheet of metal, the side edges of which engage the internal periphery of the casing, and its forward end being in abutting relation to the tube sheet 10. Thus, the casing is divided into two semi-cylindrical chambers or passes communicating with each other at the rear end of the casing. Positioned in each of the chambers are transversely extending baffles, so arranged that the fluid passing through the casing must 15 repeatedly flow back and forth transversely of the tubes, as indicated by the arrows. In the present instance, alternate baffles 20 are in the form of segments terminating at their inner edges short of the division wall 15, and the intervening baffles 21 are in the form of truncated semi-circular plates positioned in staggered relation to the baffles 20 and having their inner edges closely engaging the surfaces of the division wall 15. It 20 will be seen, particularly from Fig. 2, that the openings or slots 20* between the inner edges of the alternate plates and the dividing plate are long and narrow, and the openings or slots 21* between the outer 25 edges of the intervening plates and the internal periphery of the cylindrical casing are of less width, the result being that the stream of the fluid, flowing through the chambers, will converge as it passes through the openings 21*, and will spread out as it 30 passes through the slots or openings 20*; also, the medium within the shell is agitated by its reversal of flow and the fact that the direction of flow is across the tubes, thus 35 insuring that there will be no stratification. 40 In the drawing, I have shown by means of

arrows the directions of travel of the two media, and it will be seen that the current of one medium is counter to the current of the other medium in both passes of 50 the apparatus. Owing to the baffles, the fluid flowing about the pipes is given a relatively long course of travel during which it flows repeatedly back and forth transversely of the pipes. Also, the headers, the pipes, 55 the baffles and the division wall may be removed as a unit from the shell.

It is, of course, obvious that my invention is susceptible of various modifications and changes which are within the spirit of the invention without departing from the scope of the following claims; it being understood that the present disclosure of my invention is by way of illustration only and it is not to be taken as restrictive of my 60 conception. Also, it is evident that the double tube sheet arrangement may be used to advantage without employing the specific baffle construction described and that, while I have shown a two pass construction both 65 for the medium within the shell and within the tubes, the arrangement may be such that more than two passes are provided for each medium.

I claim as my invention:—

In a device of the character described, a cylindrical shell, a longitudinally extending wall therein dividing said shell except at its rear end into a pair of semi-cylindrical passes or chambers, a plurality of tubes in each chamber and arranged in series, and a plurality of baffle plates in each chamber, alternate baffle plates being in the form of segments terminating at their inner ends short of said division wall and the intervening baffles being arranged in staggered relation to the alternate ones and being in the form of truncated semi-circular plates with their inner edges engaging the surfaces of said division wall.

WILLIAM H. RIPLEY.
